[57] CLAIM

The ornamental design for an automobile tire, as shown and described.

DESCRIPTION

FIG. 1 is a perspective view of an automobile tire showing our new design, it being understood that the tread pattern is repeated uniformly throughout the circumference of the tire;

FIG. 2 is a front view thereof;

FIG. 3 is a top view thereof, the bottom view being substantially the same of that shown;

FIG. 4 is a rear view thereof; and,

FIG. 5 is a left side view thereof, the opposite side being substantially a mirror image of that shown.

FIG.1

FIG.2

FIG.3

FIG.4
